The ornamental design for a leg protector, as shown and described.

DESCRIPTION

FIG. 1 is an exploded perspective view of a leg protector showing our new design, the leg and shoe shown in broken lines are for illustrative purposes only and form no part of the claimed design;

FIG. 2 is a top plan view thereof;

FIG. 3 is a left side elevational view thereof;

FIG. 4 is a rear elevational view thereof;

FIG. 5 is a right side elevational view thereof;

FIG. 6 is a front elevational view thereof; and,

FIG. 7 is a bottom plan view thereof.

The crosshatch shading shown in all views is understood to repeat throughout the indicated area.
